(57) **CLAIM**

The ornamental design for a slider for reclosable fastener, as shown and described.

DESCRIPTION

FIG. 1 is a top perspective view of a slider for reclosable fastener showing our new design;

FIG. 2 is a top plan view thereof;

FIG. 3 is a right side elevational view thereof;

FIG. 4 is a left side elevational view thereof;

FIG. 5 is a front elevational view thereof;

FIG. 6. is a rear elevational view thereof; and,

FIG. 7; is a bottom plan view thereof.

The broken lines showing the slider top portion, separator finger and the inwardly directed shoulders are for illustrative purposes only and form no part of the claimed design.
